US00D998968S

(12) **United States Design Patent** (10) **Patent No.:** **US D998,968 S**
(45) **Date of Patent:** **** Sep. 19, 2023**

(54) **CASE WITH EARPHONES**

- (71) Applicant: **Apple Inc.**, Cupertino, CA (US)
- (72) Inventors: **Christina J. Smiechowski**, West Hollywood, CA (US); **Duy P. Le**, Los Angeles, CA (US); **Jeffrey Scott Croyle**, San Francisco, CA (US); **Matthew Phillip Casebolt**, Fremont, CA (US); **Matthew Vincent Costello**, Soquel, CA (US); **Christopher Wiita**, West Hollywood, CA (US); **Vijay Karthik Koneru**, Los Angeles, CA (US); **Robert Boyd**, Los Angeles, CA (US); **Joseph F. Dembs**, Los Angeles, CA (US); **Elvin Chu**, San Francisco, CA (US); **Guillaume Raoult**, San Francisco, CA (US); **Zu-Ning Chen**, San Francisco, CA (US); **Christopher Kuh**, San Francisco, CA (US); **Robert Brunner**, Glen Ellen, CA (US)
- (73) Assignee: **Apple Inc.**, Cupertino, CA (US)

(**) Term: **15 Years**

(21) Appl. No.: **29/805,594**

(22) Filed: **Aug. 27, 2021**

(51) LOC (14) Cl. **03-01**

(52) U.S. Cl.

USPC **D3/274**; D3/294; D13/108

(58) **Field of Classification Search**

Assistant Examiner — Jillian Mazzola

(74) *Attorney, Agent, or Firm* — Sterne, Kessler, Goldstein & Fox PLLC.

(57) **CLAIM**

The ornamental design for a case with earphones, as shown and described.

DESCRIPTION

FIG. 1 is a top front perspective view of a case with earphones showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the case with earphones that form no part of the claimed design.

1 Claim, 8 Drawing Sheets
